UNITED STATES PATENT OFFICE.

GEORGE FORGACH, OF GLENLYON, PENNSYLVANIA.

DESIGN FOR A DRINKING VESSEL.

SPECIFICATION forming part of Design No. 35,557, dated January 7, 1902.

Application filed November 18, 1901. Serial No. 82,782. Term of patent 7 years.

To all whom it may concern:

Be it known that I, GEORGE FORGACH, a citizen of the United States, residing at Glenlyon, in the county of Luzerne and State of Pennsylvania, have invented and produced 5 a certain new and original Design for Drinking Vessels; and I do declare the following to be a full, clear, and exact description of the invention, such as will enable others skilled 10 in the art to which it appertains to make and use the same.

This invention relates to a new and original design for a drinking vessel; and it consists of the design shown in the accompanying 15 drawings, in which—

Figure 1 is a view of the vessel taken from one side, and Fig. 2 is a view taken from the opposite side.

The leading feature of the design comprises a vessel having upon one side the representation of a professional man and upon the other side the representation of a miner, each representation being inclosed within a border consisting of implements and tools of the miners' profession—namely, shovels, picks, and 20 miners' lamps.

I claim—

The design for a drinking vessel, substantially as herein shown and described.

In testimony whereof I have hereunto set 30 my hand in presence of two subscribing witnesses.

GEORGE FORGACH.
